PICTURE TRANSMITTER

Cesar A. Castro, New York, N. Y.

Application January 2, 1935, Serial No. 82

2 Claims. (Cl. 178—7.2)

This invention relates to electromagnets generally and more specifically to those usable in television systems for the discharge of the electric charges stored in the photocells forming the photo-electric-light-sensitive screen.

To effect the discharge, in sequence, of the minute photocells forming the light-sensitive screen several methods have been proposed in the past including two types of electronic discharge. In one of these methods a pencil of light scans all points of the screen in order to cause a discharge of electrons with variable potential according to the intensity of the photo-electric charge stored in each individual cell, the separate discharges being collected by a suitable anode for transmission in the usual way. In the other method instead of using a pencil of light an electronic ray from a cathode tube is employed to neutralize the positive charges in the cells and discharge the series of cells in sequence through a suitable conductor.

Neither of these methods has proven entirely satisfactory in practice because both the light pencil and the electronic ray, probably due to dispersion of the particles or for other reasons, will cover several photocells at the same time and, therefore, their discharge is not effected in perfect sequence. The result is that the reproduced image lacks the necessary resolution or detail.

With the foregoing in mind, one of the principal objects of this invention is to provide electromagnetic means by which the discharge of the photocells forming the light sensitive screen is effected in perfect sequence due to the fact that the cells are discharged under the influence of the E. M. F. created by the wave flowing through the magnet winding opposite the cell rows in similar formation.

Another object of the invention is to provide a novel type of electromagnet, mainly for use in connection with television systems, for uniformly discharging the photocells forming the sensitive screen of a television transmitter.

Still another object of the invention is to provide electro-magnetic means to reproduce in the receiver of a television system the modulated current received from the transmitter for the conversion of the electric impulses into light.

Other objects and advantages of the invention will be come apparent from the following description and appended claims taken in connection with the accompanying drawing, in which:

Fig. 1 is a perspective end view of the electromagnet made in accordance with this invention;

Fig. 2 is a perspective front view of the same electromagnet;

Fig. 3 is a diagrammatic view of the electromagnet of this invention associated with other parts of a television transmitter.

Fig. 4 is a perspective lateral view of a modified form of electromagnet embodying the principles of this invention;

Fig. 5 is a front view, partly broken away, of a light-sensitive screen adapted for use in connection with the electro-magnet according to the present invention.

Referring now to the accompanying drawing and in particular to Figs. 1 and 2, the numeral 10 indicates the core of the electromagnet, made 15 of magnetic or other suitable material. The numeral 14 represents the winding of the magnet and to simplify the illustration only a few turns of the magnet are shown.

According to the present invention, the discharge of all the minute photocells 16 is effected in absolute sequence due to the fact that they successively come under the influence of an instantaneously created electromagnetic field by following the path of the wave crest flowing 25 through the electromagnet winding 14. This action is similar to that of an induction coil and for this reason I call the magnet of this invention an "induction electromagnet". The latter comprises a core 10 consisting of a flat plate 30 of magnetic or other suitable material, either of open pole or of closed magnetic circuit type; the winding 14 is preferably made of a single layer of wire closely wound in a number of turns equal and parallel to the lines or rows of photocells 35 16' forming the light-sensitive television screen 16 which will be more fully described hereinafter.

In Fig. 3 the electromagnet of the present invention is shown associated with other parts of a television transmitter of any suitable construction, in which the numeral 16 indicates the usual light sensitive screen, 25 indicates the anode, 18 represents a lens or glass plate forming a part of the photographic device 18', 20 indicates the frame of the apparatus, 22 is one of the threaded 45 bolts used to secure the photographic device upon the frame 20, and 24 denotes the back wall of the apparatus shown. The electromagnet is placed in magnetic contact with one of the surfaces of said light sensitive screen 16 in order 50 that all the photo-cells 16' may be under the direct influence of the induced magnetic flux or E. M. F. for the sensitive discharge of the photocells. The light sensitive screen 16, shown in Fig. 5, comprises a series of photo-electric cells 55

16' arranged in rows and insulated from one another by means of any suitable dielectric material. Screen 16 is provided with a series of electrical conductors 26 for collecting and transmitting the modulating currents produced by the photoelectric cells 16' to the amplifier for further transmission.

Fig. 4 represents a modified form of electromagnet in which the core 10 is formed of a relatively wide plate taking the shape of a quadrangular or oblong ring in cross section, and the winding 14a is made of thin wire closely wound in such a way as to present a number of turns equal and parallel to the lines or rows of photocells forming the light sensitive screen.

The operation of the electromagnet of the present invention and its influence upon the light sensitive screen are described in the following: When an object is placed in front of the photographic device 18', illustrated in Fig. 4, the individual photoelectric cells 16' of the light sensitive screen 16 become electrically charged in accordance with the light values of the object. The winding 14 of the electromagnet is connected to a source of current (not shown) and the current interrupted intermittently. Each interruption of the current flowing through the winding 14 of the electromagnet will set up an electromagnetic field and as a result induction currents will flow from the photoelectric cells 16' through the surrounding dielectric insulating material of the screen 16 to the conductor 26 leading to the amplifier. The modulation current thus produced will be of varying intensity depending upon the charges of the photoelectric cells which in turn correspond to the different light values of the object. My electromagnet is constructed in such manner that each turn of the winding 14 lies parallel with and corresponds to a row of photoelectric cells 16'. The electric current flowing through the first turn of the winding 14 thus causes the discharge of the first row of photoelectric cells 16' and when the current enters into and flows through the second turn of the winding 14, the second row of cells 16' are discharged and so on. As the current flows through each turn of the winding 14 the individual cells 16' discharge successively their respective charges and inasmuch as the winding

14 comprises exactly the same number of turns as there are rows of cells 16', the latter are always discharged in proper sequence.

In connection with the receiver of a television system, the induction electromagnet of this invention is placed adjacent to the receiver plate preferably formed of lines or rows of conductive cells or wires corresponding to the lines or rows of photocells forming the transmitter light-sensitive screen (Fig. 5). The modulated current intermittently flowing through the induction electromagnet will create relatively strong electric impulses in the conductive cells or wires of the receiver plate and these electric impulses may be converted into light for the reproduction of the view or image in any manner well known to the art. In my co-pending application Serial No. 719,876 a receiver plate formed of a mosaic of wires is disclosed, which may be well adapted to use in connection with the induction electromagnet of the present invention.

Various modifications and changes may be made in the apparatus described without departing from the spirit of the invention and, therefore, my invention should be interpreted as including such changes and modifications with no other limitations than those derived from the scope of the appended claims.

I claim:

1. An induction electromagnet adapted for use in a television system comprising a light-sensitive screen formed of a plurality of photocells, said electromagnet comprising an angular core having at least one flat, relatively wide side and a winding of covered wire closely wound carried by said core on the said flat side thereof, said flat side being disposed adjacent to the said screen.

2. In a television system, the combination of a light sensitive television screen comprising a plurality of photoelectric cells disposed in rows with an electromagnet consisting of a core and a wire winding thereon, each turn of the winding corresponding to a row of cells and being disposed parallel thereto and conductive means adjacent said cells, said electromagnet and screen being in electromagnetic contact with each other and spaced apart to establish a gap therebetween.

CESAR A. CASTRO.
